ATTORNEY

UNITED STATES PATENT OFFICE

SYDNEY ROGER CAVE, OF NEW YORK, N. Y.

DUPLEX INDICATING DEVICE

Application filed January 19, 1929. Serial No. 333,627.

The device, the subject of this invention, is an indicating device, particularly adapted for indicating telephone numbers or radio stations, or any other series of characters where 5 a plurality of numbers or a series of numbers and letters are required to coincide to complete an indication.

In the past, it has been customary to use what are commonly termed logs, or books, or 10 cards, wherein or whereon the numbers and characters are written in ink or pencil, but because of the constant changes that are made in such memoranda, the book or log becomes useless in a short time.

15 An object of my invention, then, is to provide means whereby numbers or characters or both may be changed at will, and may be changed without destroying or making useless, any part or parts of the record device.

20 The following is what I consider the best means of carrying out my invention, and the accompanying drawings should be referred to for a complete understanding of the specification which follows.

25 In the drawings:—

Fig. 1 is a side elevation of my device, the enclosing casing being shown in section.

Fig. 2 is a front elevation.

Fig. 3 is a back elevation.

30 Fig. 4 is a perspective view of one of the card holders.

Similar reference numerals indicate like parts in all the figures where they appear.

At 1, I show a face plate, the bottom portion 35 2 of which is turned backward to provide a stand or base or support for my device. This face plate 1 is provided with a window 3, and a plurality of slots 4, extending radially from a point 5, wherein is arranged a pivot 40 for a lever 6. The lever 6 is provided with an operating handle 7, and a pointer 8, the pointer extending inward over the face plate 1. Arranged in each or any of the slots 4, is a sliding member 9, which is a card holder, 45 and which is shown in detail in Fig. 4.

Formed integral with the face plate 1, or the base 2, are upwardly extending members 10 and 11, which serve as supports and bearings for a shaft 12, and upon the shaft 12 is a 50 drum 13 and a pin driven slotted drum or

gear 14. Formed integral or secured to the lever 6, is a sector 15 provided with a plurality of pins 16, any one of these pins may enter a slot 17 in the member 14 to rotate this member. The drum 13 is provided with a plurality of slots 18, and the drum 13 may be formed of wood, and upon the drum 13 and overlapping the slots 18, are metallic strips 19. Cards such as those shown at 20, may be slipped into the slots 18, to be retained there- 55 in by the strips 19.

In the operation of this device, one or more of the card holders shown in Fig. 4, is placed in each of the slots 4 on the face plate 2, and thereafter cards may be inserted into these 60

card holders. 65 If the dial is to be used with a three-dial radio set, then the letters indicating the stations, will be placed in the card holders, as suggested at 9, and thereafter series of cards carrying figures indicating the dial settings, will be arranged in the slots 18 of the cylinder 13, and now when the knob 7 is rotated so as to bring the pointer 8 adjacent one of the cards in the slots 4, the proper dial settings will appear through the window 3. 70

It will of course be understood that any series of letters or figures or duplex series of figures and/or letters, may be employed.

I may, if desired, enclose the back of my 80 device as suggested by the housing 21. I may of course increase or decrease the number of slots in both the face plate and the drum, correspondingly changing the number of pins in the sector 15, and the number of 85 recesses in the gear member 14.

The blank portion of the face plate 1, under the window 3, may be used for advertising, or I may place thereon, alternate station readings, or other information, and other modifications may be made within the scope of the appended claims without departing from the principle or sacrificing the advantages of this invention. 90

Having carefully and fully described my 95 invention, what I claim and desire to secure by Letters Patent is:—

1. A device of the character described comprising a plurality of movable card holders, and a plurality of stationary card holders, a 100

5 rotatable means for supporting certain of said movable card holders to cause them to correspond with the fixed position of the stationary card holders, said means comprising a sector member and a gear and shaft operated thereby and a drum upon said shaft.

10 2. An indicating device comprising a face plate, having a plurality of slots therein, and card holders adapted to be introduced into said slots, a ring-shaped member, a shaft for supporting said ring-shaped member, and a plurality of pins in said ring-shaped member, a rotatable slotted member and a drum secured together, the pins in said ring-shaped member being adapted to enter the slots in said slotted member to rotate said drum.

15 3. An indicating device having a face plate provided with a slot, movable card holders supported thereon, a drum at the back of said face plate and adjacent thereto, a rotatable slotted member, and a rotatable ring-shaped member having means for engaging said slotted member and a shaft extending through said slotted member and said drum for rotating said drum upon the movement of said ring-shaped member.

SYDNEY ROGER CAVE.
